INVENTOR

Beth. A. Stocking.

67 Diving & Flagg. 1775.

UNITED STATES PATENT OFFICE.

BERT A. STOCKING, OF DENVER, COLORADO, ASSIGNOR TO FRANK R. STEELSMITH, TRUSTEE, OF DES MOINES, IOWA.

WRINGER.

Substitute for previously abandoned application Serial No. 50,945, filed August 18, 1925. This application filed July 7, 1928. Serial No. 291,145.

The object of my invention is to provide a wringer of simple, durable and inexpensive construction, having one of the wringer rolls adjustably and yieldably mounted relative 5 to the other in such a manner that a considerable amount of movement is provided between said rollers, and in connection therewith to provide means whereby the said rollers may be easily and quickly thrown out of 10 operative relation with each other.

My invention consists in the construction, arrangement and combination of the various parts of the device, whereby the objects contemplated are attained, as hereinafter more 15 fully set forth, pointed out in my claims, and illustrated in the accompanying drawings, in which:

Figure 1 shows a side elevation of my improved wringer, a portion of the frame being 20 broken away to show in detail certain mechanism.

Figure 2 is an end elevation of the same, showing one portion of the spring housing broken away.

Figure 3 is a detail sectional view taken 25 on the line 3—3 of Figure 1; and

Figure 4 is a detail sectional view taken on the line 4—4 of Figure 1.

My improved device comprises a supporting bracket 10, which is of the swinging type, and is provided at its upper end with a gear housing 11 in which is enclosed the ordinary wringer driving and reversing mechanism. The member 10 is provided with a bracket 12, 30 to which is secured the wringer frame 13. Said frame member comprises a horizontal portion 14, each edge of which is provided with an inclined plate 15, said plates being formed integral with the member 14 and 35 serve to form the drain boards.

Each end of the member 14 is provided with a guide block 16, each of said guide blocks being provided with an opening 17 near its upper surface in which is mounted a 40 roller shaft 18, said shaft being designed to carry the roller 19 and having one end extending into the gear housing 11, said roller 19 being mounted above the member 14, as clearly shown in Figures 1 and 3.

50 In each end of the member 16 I have provided a pair of vertical openings 20, each

of said openings being provided with a sleeve 21, which is slidably mounted therein. The upper end of each pair of sleeves 21 is provided with a block 22, which provides means 55 for rigidly mounting said sleeves, the blocks 22 being connected by means of a frame member 23. The head members 22 are provided with a shaft 24 on which is mounted a roller 25.

Thus it will be seen that the members 22 and 23 form a rigid frame having sleeves 21 which are slidably mounted in the member 16, and designed to carry the roller 25, so that 60 said roller may be moved from and toward the roller 19.

For actuating the up and down movement of said frame, I have provided at the lower end of the pair of sleeves 21 a bar 26, which is provided at each end with a bolt 27 which 70 extends upwardly into the sleeve 21 and has at its upper end a head 28. A spring 29 is provided for each of the bolts 27, the lower end of the spring resting against an inwardly turned flange 30 at the lower end of the 75 sleeves.

Adjacent to the lower edge of one of the members 15 I have provided a pair of lugs 31, each of which is provided with a circular opening 32. Each of the openings 32 is provided with a disc 33, which is rotatively mounted therein. A shaft 34 extends through both of said discs 33 and is placed therein in an eccentric manner, one end of the shaft 34 being provided with a lever 35.

80 Adjacent to the outer face of each of the discs 33 I have provided a lever 36, one end of which is pivotally connected at the lower edge of the side flanges 37 of the member 15 by means of the pivot 38. The opposite end 85 of the lever 36 is provided with a slot 39, said slots being designed to receive a rod 40 which connects both of said members 26 near their central portions. Each of the levers 36 is also provided with a slot 41, said slots 41 90 being designed to receive the shaft 34.

95 Referring to Figure 2, it will be seen that the lever 35 is placed at a position where it inclines slightly below the horizontal, and that the discs 33 are so adjusted relative to 100 said lever that the inner ends of the levers 36 will be moved to an elevated position and

the block 26 caused to engage the lower ends of the sleeves 21 and to slide said sleeves upwardly through the block 16 in such a manner that the roller 25 will be separated a considerable distance from the roller 19. This is the normal position of the wringer rolls when not in use.

When it is desired to operate the wringer, the lever 35 is swung from position illustrated in Figure 2, to the position shown in Figures 1 and 3, which will cause the discs 33 to be rotated and the shaft 34 to be lowered, which in turn will cause the inner ends of the levers 36 to be lowered and the bars 26 and the roller 25 lowered until the said roller 25 engages the roller 19. A further movement of the lever 35 will cause the bar 26 to move downwardly from the ends of the members 21, and tension will be applied to the springs 29, which in turn will cause tension to be applied to the roller 25.

By this construction it will be seen that the sleeves 21 may be provided comparatively long, which will enable long springs to be used therein, which will permit a comparatively large amount of yieldable movement while under tension between the wringer rollers, permitting heavy pieces of material, such as bed clothes, and the like, to be operated on.

It will be seen that the tension between the said wringer rollers may be almost instantly released by simply throwing the upper end of the handle 35 outwardly, which will not only release the tension but will also throw the upper wringer roller away from the lower wringer roller, permitting any articles to be conveniently and quickly removed.

The slots 41 are of such length, and arranged in such manner, that when the lever 25 is in vertical position, the shaft 34 will engage the outer end of the slot, the disc being arranged in such position that the tension on the levers 36 and the springs 29 will cause the said shaft 34 to be rotated toward the end of said slot, thereby supporting the lever 35 permanently in a vertical position without the use of catches or similar devices. In other words, the shaft 34 is mounted in such a manner as to slightly pass the center of the disc 33. By this arrangement it will be seen that the tension on the roller 25 may be instantly released without having to release any catch device, as has heretofore been the practice. Such catches usually stick or in some other way become inoperative.

Thus it will be seen that I have provided a wringer of simple, durable and inexpensive construction, in which the rollers are yieldably supported relative to each other in such a manner that a considerable amount of movement is provided for receiving goods of various thicknesses, and provided with means whereby the tension may be instantly released.

This application is a substitute for my previously abandoned application 50,945 which was filed Aug. 18, 1925.

I claim as my invention:

1. A wringer comprising a frame, a roller 70 rotatively mounted therein, a second frame member adapted to move toward and from the first said frame member, a roller in said second frame member, yieldable means for moving the first frame member toward the 75 second frame member, means for moving said first frame member from the second frame member against said yieldable means, comprising a shaft having a pair of eccentrically mounted disks, a lever secured to said shaft 80 and means for operatively connecting said eccentricities with said frames in such a manner that as the lever is operated and the shaft rotated the said frame members will be separated. 85

2. A wringer comprising a horizontal frame member, each edge of which is provided with a downwardly and outwardly extending flange, each end of said frame member being provided with a pair of vertical 90 openings, a second frame member above the first said frame member, having each end provided with a pair of downwardly extending sleeves slidably mounted within the openings of the first frame member, a wringer roller for each of said frame members, a bar beneath each pair of said sleeves, a bolt in each end of each of said bars, said bolts extending upwardly into said sleeves, a spring between the upper end of each of 100 said bolts and the lower end of each of said sleeves, means for moving said bars downwardly for moving said frame members together and for applying yieldable pressure between said rollers, and means for quickly 105 releasing said pressure and elevating the said second frame member. 95

3. A wringer comprising a horizontal frame member, each edge of which is provided with a downwardly and outwardly extending flange, each end of said frame member being provided with a pair of vertical openings, a second frame member above the first said frame member, having each end provided with a pair of downwardly extending 110 sleeves slidably mounted in the openings of the first frame member, a wringer roller for each of said frame members, a bar beneath each pair of said sleeves, a bolt in each end of each of said bars, said bolts extending upwardly into said sleeves, a spring between the upper end of each of said bolts and the lower end of each of said sleeves, means for moving said bars downwardly to move said frame members together and for applying 115 yieldable pressure between said rollers, and means for quickly releasing said pressure and elevating the said second frame member, said last means comprising a pivoted lever for each of said bars, each of said levers having 120 125 130

its free end pivoted to one edge of one of said downwardly and outwardly extending flanges, an eccentric device for imparting upward and downward movement to the movable ends of said levers, and a lever for operating said eccentric.

4. A wringer comprising a frame member, a wringer roller in said frame member, a second frame member, a wringer roller in said second frame member, means for moving one frame member toward and from the other frame member and in parallel relation with each other, a lever pivotally connected to each end of said moving means, means for pivotally connecting the opposite ends of said levers to the first frame member, a disc adjacent to each of said levers and rotatively mounted in the first frame member, each of said levers being provided with a slot, a shaft extending through both of said slots and said disc and eccentric to said disc, and a lever for one end of said shaft, said moving means including means for applying yieldable pressure to press said rollers together when said levers are in one position of their movement.

5. A wringer comprising a frame member, a wringer roller in said frame member, a second frame member, a wringer roller in said second frame member, means for moving one frame toward and from the other frame member in parallel relation with each other, a lever pivotally connected to each end of said moving means, means for pivotally connecting the opposite ends of said levers to the first frame member, a disc adjacent to each of said levers and rotatively mounted in the first frame member, each of said levers being provided with a slot, a shaft extending through both of said slots and said disc and eccentric to said disc, and a lever for one end of said shaft, said moving means including means for applying yieldable pressure to press said rollers together when said levers are in one position of their movement.

Des Moines, Iowa, April 26, 1928.

BERT A. STOCKING.
